United States Patent Office

Des. 187,608
Patented Apr. 5, 1960

187,608

CLOCK

Denis Francis Merrigan, Toronto, Ontario, Canada

Application July 7, 1958, Serial No. 51,658

Term of patent 14 years

(Cl. D42—7)

Figure 1 is a front elevational view of a clock, showing my new design; and

Figure 2 is a side elevational view thereof.

I claim:

The ornamental design for a clock, as shown.
